(57) **CLAIM**

The ornamental design for a portable tool caddy, as shown and described.

DESCRIPTION

FIG. 1 is a perspective view of a portable tool caddy of the present invention, showing the portable tool caddy having a flat base vertically extending wall surface substrate, with a carry handle, having a manually graspable hole, and having a bottom recess for mounting atop a typical wheeled luggage or rolling tool bag, sets of fastener clasps, and showing a plurality of pockets for tools and a shoulder strap;

FIG. 2 is a front elevation view of the portable tool caddy; FIG. 3 is a rear elevation view of the portable tool caddy; FIG. 4 is a left side elevation view of the portable tool caddy; FIG. 5 is a right side elevation view of the portable tool caddy;

FIG. 6 is a perspective view of a portable tool caddy, showing the portable tool caddy mounted atop a typical wheeled luggage or rolling tool bag;

FIG. 7 is a perspective view of a portable tool caddy, showing the portable tool caddy rolled and carried by the shoulder strap upon the shoulder of a user; and,

FIG. 8 is a perspective view of the portable tool caddy, shown rolled and carried by a hand of the user manually grasping the handle of the portable tool caddy, and showing alternative sets of overlapping fastener clasps.

The wavy horizontally extending cutaway lines in the drawing figures indicate height adjustability of the portable tool caddy.

The depiction of the wheeled luggage or rolling tool bag, the plurality of pockets for tools, the sets of fastener clasps and the shoulder strap on the portable tool caddy, and the person depicted as a user are shown for environmental purposes in dashed lines, and form no part of the claimed design.

The broken lines depict environment and are included for the purpose of illustrating only and form no part of the claimed design.

The caddy is shown broken away to indicate that no particular length is claimed, any portion shown between forms no part of the claimed design.
